UNITED STATES PATENT OFFICE.

ERNEST A. RICKER AND JAMES F. DOBBIN, OF JACKSONVILLE, FLORIDA.

BOTTLE-FILLER.

1,276,269.

Specification of Letters Patent. Patented Aug. 20, 1918.

Application filed March 1, 1917. Serial No. 151,799.

To all whom it may concern:

Be it known that we, ERNEST A. RICKER and JAMES F. DOBBIN, citizens of the United States, residing at Jacksonville, in the county of Duval and State of Florida, have invented certain new and useful Improvements in Bottle-Fillers; and we do declare the following to be a full, clear, and exact description of the invention, such as will enable others skilled in the art to which it appertains to make and use the same.

Our invention has for its object to provide an extremely simple and inexpensive yet a highly efficient apparatus for rapidly and equally distributing a predetermined quantity of liquid into a number of bottles or other containers, and with this general object in view, the invention resides in the novel features of construction and unique combinations of parts to be hereinafter fully described and claimed, the descriptive matter being supplemented by the accompanying drawings which constitute a part of this application and in which:

25 Figure 1 is a front elevation of the improved apparatus;

Fig. 2 is a vertical sectional view thereof on the plane of the line 2—2 of Fig. 1;

30 Fig. 3 is a vertical section at right angles to Fig. 2 taken on the plane of the line 3—3 thereof;

Fig. 4 is a horizontal section on the plane of the line 4—4 of Fig. 2.

In the drawings above briefly described, 35 the numeral 1 has reference to a flat horizontal base from which a pair of vertical boards or other suitable supports 2 rise, the lower ends of the rear edges of said boards being braced by a strip 3 secured thereto 40 and to the base 1. The upper ends of the boards 2 support thereon a top-board or bottle support 4 having an opening 5 through which the neck N of the large bottle B of liquid to be distributed is inserted 45 into the tilting receptacle 6.

The receptacle 6 is closed on all sides with the exception that it is provided with an opening 7 in its top aligned with the opening 5, said receptacle having a channel-shaped bottom 8 which is preferably in the form of a V in transverse section. From the lowest

point of this bottom, a plurality of siphon tubes 9 incline upwardly and outwardly to a point 10 and at this point are bent downwardly to form discharge nozzles 11 for insertion in the necks of the bottles. The receptacle 6 is provided with an operating handle 12 by means of which it may be tilted as hereinafter described but a spring catch 13 co-operates with said handle 60 to normally prevent movement of said receptacle.

To permit the use of the apparatus for filling bottles with more or less liquid, the journals 14 upon which the receptacle 6 is mounted are preferably receivable in any of the angular notches 15 formed in bracket plates 16 which are by preference secured to cleats 17, the latter being in turn fixed to the inner faces of the side boards 2. The receptacle is thus rendered quickly and easily adjustable to different heights so that it will be filled to a greater or less extent by the bottle B.

A bottle supporting platform 18 is carried by a horizontally disposed frame 19 whose rear portion is disposed between the side boards 2 and fulcrumed at 20 to brackets 21 secured to said boards, coiled springs 22 being connected at their opposite ends to the frame 19 and the base 1 for returning the latter to normal position. The upward movement of the platform 18 is limited by L-shaped stops 23 adjustably secured to brackets 24 carried by the inner sides of the boards 2. By adjusting the stops 23, the frame 18 may swing upwardly to a greater or less extent to adjust the machine for filling bottles of different sizes. The rear edge of the platform 18 is by preference provided with an upstanding wall 25, said wall serving to retain the bottle container 26 in proper position upon the platform as shown clearly in the drawings.

In operation, the bottle B of liquid to be distributed into the bottles is inverted so that its neck N projects through the openings 5 and 7 into the receptacle 6, the latter being held against tilting by the spring catch 13, and said receptacle will thus be filled until the liquid therein cuts off the entrance of air into the bottle B. The bot-

tles to be filled are now placed in the container 26 and the latter is placed on the platform 18 after depressing the frame 19 sufficiently to permit insertion of the nozzles 11 into the necks of the bottles. These preliminaries having been performed, the catch 13 is released and both the platform 18 and the lever 12 are forced downwardly until the receptacle 6 is tilted sufficiently to cause the liquid to start flowing from the nozzles 11 into the bottles. Then the platform 18 is released to permit the springs 22 to restore said platform to its original location. The liquid will then be siphoned from the receptacle 6 through the tubes 9 and will be equally distributed in all of the bottles. When the liquid level in the bottles rises to that in the receptacle, which level is constantly maintained by the bottle B, the filling operation will automatically cease. The lever 12 is then returned to its normal position and the filled bottles are removed.

The apparatus is designed primarily for distributing numerous kinds of liquids from the large bottles in which they are shipped, these bottles being usually of a size to contain five gallons but it will be understood that the apparatus can be made to coöperate with any size reservoir and that this reservoir need not necessarily be in the form of a large bottle. It could well be of any suitable construction and the liquid to be distributed could be poured into the same from the containers in which it is shipped or stored.

Obviously, the machine may be made in different sizes for filling different numbers of bottles at the same time and for filling either small or large containers, although the features of construction above described permit a wide range of adjustment so that a machine constructed primarily for filling bottles of one size, may be employed to advantage for filling those which are either larger or smaller.

On account of the advantages derived from the construction shown and described, it constitutes the preferred form of the apparatus but it is to be understood that within the scope of the invention as claimed, numerous changes may be made without sacrificing the principal advantages.

We claim as our invention:

1. A liquid dispensing apparatus comprising a support for an inverted reservoir bottle, a tilting receptacle below said support into which the neck of the bottle extends, the bottom of said receptacle being V-shape in transverse section, a plurality of metal outlet tubes passing through one side of said receptacle and disposed transversely of its axis, said tubes extending across half the width of said V-shaped bottom in contact therewith and being secured thereto,

whereby said tubes are securely braced, said tubes projecting from said receptacle and having their outer ends bent downwardly for reception in the bottles to be filled, and a depressible bottle support below said downwardly bent end. 65

2. A structure as specified in claim 1, together with a bar extending transversely across the outer end of said tubes and secured thereto, and a handle secured to one end of said receptacle and secured between 75 its ends to said bar.

3. A bottle filling apparatus comprising a pair of vertical side members having brackets secured to their inner sides, said brackets having notches formed in their upper ends, a substantially horizontal frame extending between said side members at its rear end and having a bottle support at its front end, the side bars of said frame having trunnions received removably in said 80 notches, and springs secured to the rear ends of said side bars and exerting stress thereon to retain said trunnions in said notches; together with a tilting receptacle above said frame, outlet siphons from said 90 receptacle, and means for supplying liquid to said receptacle.

4. A bottle filling apparatus comprising a base, a pair of parallel vertical side members rising from said base, a horizontal reservoir bottle support resting on and secured to the upper ends of said side members, said support having an opening through which the bottle neck projects, a pair of bracket plates secured to the inner sides of said side members and having vertically spaced inclined notches, a tilting receptacle between said side members and having lateral trunnions received in said notches for adjusting said receptacle toward and away from said bottle support, the bottom of said receptacle being V-shaped in transverse section, a plurality of metal outlet tubes passing through the front side of said receptacle and extending across one-half the width of said 100 V-shaped bottom in contact therewith and secured thereto, whereby said tubes are securely braced, the outer ends of said tubes extending forwardly from the receptacle and bent downwardly for reception in the 110 bottles to be filled, a transverse bar extending across the front ends of said tubes and secured thereto, a handle secured at one end to one end of said receptacle and secured between its ends to said bar, a pair of 120 brackets below the aforesaid bracket plates and secured to the inner faces of said side members, said brackets having notches in their upper ends, a substantially horizontal frame having lateral trunnions received 125 removably in said notches, springs connected to the rear end of said frame for exerting a downward stress thereon to normally

raise the front end of said frame and retain said trunnions in said notches, adjustable stops for limiting the upward movement of the front end of said frame, and a bottle support mounted on said front end to support the bottles to be filled.

In testimony whereof we have hereunto

set our hands in the presence of two subscribing witnesses.

ERNEST A. RICKER.
JAMES F. DOBBIN.
